UNITED STATES PATENT OFFICE

HENRY N. FELEY, OF EAST ORANGE, NEW JERSEY

BOOK COVER

Application filed February 16, 1928. Serial No. 254,696.

The invention relates to book covers and more particularly to covers or cover blanks for a flat-opening check book.

The object of the invention is to produce a cover that is both simple and economical to manufacture and one that lends itself readily to being assembled by automatic machinery. The cover for this type of check book, which is disclosed in my Patent No. 1,606,213, dated November 9, 1926, comprises side cover boards, a back stiffening board, and strips adjacent and between said side cover boards and back stiffening board. When these boards and strips are all formed of separate pieces great care and accuracy must be exercised in assembling them with the outside cover sheet. The primary object of the invention is to provide a blank which may be handled as a single unit or piece when assembling it with the outside cover sheet and yet function in the complete cover as satisfactorily or more so than if the covers and strips were separate pieces.

A further object is to provide a book cover which is of extreme neatness in appearance.

The present invention contemplates cutting a series of grooves between the side cover boards, adjacent strips and back stiffening board. These grooves extend completely across the blank and are cut approximately through the blank, leaving only a sufficient amount of material to hold the boards and strips together so as to permit of the blank being handled as one piece when assembling it with the outside cover sheet. Other features of the invention will become apparent as this specification proceeds.

In the accompanying drawings forming a part hereof:

Fig. 1 is a plan view of a sheet of material from which a plurality of blanks may be cut;

Fig. 2 is a perspective view of a single blank;

Fig. 3 is a plan view of the blank with the outside cover sheet attached;

Fig. 4 is a plan view of the blank as illustrated in Fig. 3 with the reinforcing stripping and paste down sheets attached.

In this view the cover is complete and parts of the paste down sheets are broken away to show parts underneath;

Fig. 5 is a sectional view on line 5—5 of Fig. 4; and

Fig. 6 is a fragmentary end view of the completed check book.

In Fig. 1 the reference numeral 10 designates a large sheet of cardboard or similar material. This sheet has been trimmed down from a standard size sheet such as might be shipped from the mill or it might be a sheet of standard size. By means of suitable mechanism a series of grooves 11 are formed, the grooves extending the entire length of the sheet. The sheet is then cut along the broken lines 12 and a plurality of individual blanks 13 are provided. The fact that the grooves run entirely across the large sheet 10 makes for great economy of production. The operation of cutting the grooves across the large sheet is practically no more work than would be involved in cutting grooves for one blank and by this method a plurality of blanks are grooved with the one operation. The blanks 13 or large sheets 10 might be manufactured with the grooves already formed therein.

One of the blanks is illustrated in Fig. 2, in which it will be noted that the grooves 14, 15, 16 and 17 run entirely across the blank and divide it into two large cover boards 18, a back stiffening board 19 and two strips 20. The grooves are reasonably wide and are cut to a substantial depth, leaving only a sufficient amount of material to permit of the blank being handled as one piece when assembling with the cover sheet, hereinafter described. The grooves 14 and 17 are wider than the grooves 15 and 16 for a purpose later described.

The outside cover sheet 21, made of a durable grade of paper, fabric, imitation leather or other suitable material is coated with adhesive for securing it to the blank 13, or, conversely the blank may be coated with adhesive material and the cover sheet applied thereto. The margins 22 of the cover sheet are folded over and adhesively secured along the edges of the blank on the side

opposite where the cover sheet is applied, as illustrated in Fig. 3. As shown in this figure and Fig. 5, the outside cover sheet is applied to the side of the blank in which 5 the grooves are formed.

A reinforcing stripping 23 is applied to the inside of the cover blank. This reinforcing stripping is preferably secured to the cover blank over the area of the strips 10 19, 20, 20 and adjacent edges of the panels 18, 18. Paste down sheets 24 are adhesively secured to the inner sides of the cover boards 18 and the binder is then completed.

By grooving the blank as heretofore described it is obvious that in assembling it with the cover sheet it may be handled as one unit and thus save a great deal of labor and inefficiency that would be entailed in handling the cover board and strips as 20 separate pieces. The slight amount of material that is left in the grooves does not in any way interfere with the flexibility of the book at its hinge portions after complete assembly.

25 The completed book is shown in Fig. 6. The central strip 19 termed the back stiffening board forms the back 25 of the book. The adjacent strips 20 act as the binding portions 26 and the large panels 18 form 30 the covers 27. The sheets 28 are suitably bound at 29 by posts passing through the sheets and binding portions 26 in such a manner as to insure the book opening flat. The nature of the binding is disclosed in my 35 Patent No. 1,606,213, previously mentioned. The grooves 15 and 16 allow for the bends 30, while the wider grooves 14 and 17 form the cover hinges 31. As more flexibility is desired at the hinges 31 than at the bends 40 30, the grooves 14 and 17 are made wider than the grooves 15 and 16.

The cover is designed for what is commonly known as a desk check book, preferably three or more checks deep. The side 45 cover boards 18 are of appropriate dimensions for the size and number of checks and their stubs on each page. The strips 20 through which the binding posts 29 pass may be of a standard width regardless of 50 the size and number of sheets in the book and the width of the back stiffening board 19 is controlled by the number of pages in the book or the thickness of the book.

55 From the foregoing taken in connection with the accompanying drawings it is thought the operation and construction of my book cover will be clear to those skilled in the art. While a preferred form of the invention has been described and illustrated 60 various changes in size, shape, proportions and details of construction may be made without departing from the spirit and scope of the appended claims.

What I claim is:

65 1. A filler blank for a book cover, com-

prising a substantially rectangular sheet of stiff material having four parallel grooves cut across said sheet at approximately the central portion thereof, the two central grooves being narrower in width than the outer grooves, the grooves extending entirely across said filler blank and being cut approximately through said filler blank and leaving only a sufficient amount of material to permit of said filler blank being handled as one piece when assembling.

70 2. A rectangular sheet of material of sufficient size from which a plurality of check book filler blanks may be formed, said sheet having four parallel grooves at its central portion, and being adapted to be cut so as to form a plurality of filler blanks for book covers, each filler blank having four parallel grooves at its central portion.

75 3. A filler blank for a book cover, comprising a substantially rectangular sheet of stiff material having four parallel grooves cut across said sheet at approximately the central portion thereof, said grooves being cut entirely across said blank and leaving only a thin web of material so as to permit of said blank being handled in one piece.

80 In testimony whereof I affix my signature.
HENRY N. FELEY.
